UNITED STATES PATENT OFFICE.

JAMES KEWLEY, OF TOLEDO, OHIO.

EXCAVATOR.

SPECIFICATION forming part of Letters Patent No. 552,580, dated January 7, 1896.

Application filed June 24, 1895. Serial No. 553,789. (No model.)

To all whom it may concern:

Be it known that I, JAMES KEWLEY, a citizen of the United States, residing at Toledo, Lucas county, Ohio, have invented certain 5 new and useful Improvements in Excavators, of which the following is a specification.

In the use of steam excavating-machines for digging ditches, constructing sewers, and the like a common difficulty encountered has 10 been that the dipper or shovel employed has interfered with the banks or sides of the excavation, so that instead of making a cut with smooth slopes or sides the cut has been ragged and uneven. This is owing to the fact that 15 when the crane upon which the shovel or dipper is mounted is swung to the right or left of the central line of the excavating-machine the cut of the dipper has been on lines radiating from the mast of the crane and corresponding with the angle at which the crane 20 is set.

My invention relates to and its object is to provide means for overcoming the difficulty here pointed out; to provide an attachment 25 for an excavating-machine by means of which the dipper or shovel shall be enabled to cut on lines parallel with the central line of the machine, regardless of the angle at which the crane shall be set, and to so construct a dipper 30 or shovel that its bail and other appurtenances shall not come in contact with the banks or prevent an even surface being formed by the shovel or dipper. I attain these objects by means of the mechanism and arrangement of 35 parts hereinafter described, and shown and illustrated in the accompanying drawings, made part hereof, in which—

Figure 1 is a side elevation of my device; Fig. 2, a plan view and diagram of part of 40 the same, that part of the mast 20 hereinafter referred to above the sheaves 20°, hereinafter referred to, being removed and the supplemental mast 2^a, hereinafter referred to, being also removed; Fig. 3, a plan view illustrating 45 the mode of pivotally connecting the outer extremity of the crane and the supplemental boom or extension-piece, hereinafter referred to; Fig. 4, a side elevation, partly in section, of the same; Fig. 5, an elevation, partly in section, of a mast and brace, hereinafter referred to; Fig. 6, an elevation of my crane 50 without its attachment in use as in a common

excavating-machine; Fig. 7, a central vertical longitudinal sectional elevation of my dipper or shovel, showing its interiorly-pivoted bail, brace and dipper-arm connection, hereinafter referred to; Fig. 8, a front end view of the same, and Fig. 9 a plan view of a portion of the same.

Like numerals represent like parts throughout the drawings.

In the drawings, 1 represents a car, wagon, or other vehicle, upon which is mounted a crane, consisting of the usual mast 2, boom 3, and brace 4. This crane is provided with the 65 usual swinging circle 5, by means of which the crane is swung by rope or chain passing around said circle in the usual manner, and which need not be further described. At the outer extremity of the crane, near the meeting-point of the brace and boom 3 4, is pivotally attached, as hereinafter described, a supplemental boom or extension-piece 6, preferably inclined downwardly and provided with a swinging circle 7, actuated by rope or chain 75 8, leading preferably to a drum 9 on the crane, governed by a small engine 10, mounted on the crane, as shown in Figs. 1 and 2. The supplemental boom or extension-piece 6 is made in two pieces with a space between the 80 two for the dipper-arm 11, provided with the usual rack 12, engaged by pinion 13, journaled in the two pieces forming boom 6. Upon the shaft of pinion 13 are fixed friction-wheels 14, engaged by friction-straps 15, adapted to be 85 tightened or loosened by means of lever 16. From this lever leads a rod or cord (not shown in the drawings) to within convenient reach of the operator. The dipper stick or handle 90 11 carries at its lower end a dipper or shovel 17, which is raised and lowered by means of chain 18, leading over pulley 19, journaled on extension-piece 6 to the hoisting-drum on the car. (Not shown in the drawings.)

In applying my supplemental boom or extension-piece 6 to an excavator-crane, it is necessary to brace this extension from the car, so that it shall not yield to the heavy strains to which it is subjected. To accomplish this I provide the mast 2 with an extension 2^a, 100 stepped or seated at its lower end in a sleeve 2^b, which is loose upon the mast 2. To this sleeve is secured the swinging circle 5 and the extension-mast 2^a, and they together ro-

tate upon the upper end of mast 2, which is stationary. The top of extension-mast 2^a is loosely socketed in a stationary cap 2^b, from which lead to the car braces 2^c. The swinging circle 5 is braced and supported by rods or braces 5^a leading from the circle to the upper part of extension-mast 2^a. Upon the outer extremity of the crane 2 3 4 is set a short mast 20. This mast at bottom is square, as at 20^a, (see Fig. 5,) and is stepped in a square socket, as at 20^b, (see Figs. 3 and 4,) in the top of boom 3, which prevents the turning of the mast 20 upon its longitudinal axis. The extreme lower part of this mast 20^c is round and forms a stout bolt or pin, passing through the jaw of the outer extremity of boom 3 (see Fig. 6) and through the tongue or tenon 6^a of the supplemental boom or extension-piece 6, where the two are united, forming a pivot 20 upon which the extension-boom swings. This mast immediately above its seat has formed upon it, and preferably integral therewith, a housing 20^d, (see Fig. 5,) in which are journaled two guide-sheaves 20^e, between which passes the hoisting-chain 18, the two guide-sheaves permitting the chain to run freely, regardless of the direction in which the supplemental boom 6 may be turned. The top of the mast 20 is reduced in size, as at 20^f, and is provided with a shoulder, as at 20^g, which takes loosely a sleeve 21 resting upon the shoulder 20^g. To the extreme upper part of mast 20 is rigidly secured a cap 22. (See Fig. 1.) From the top of extension-mast 2^a, and swinging therewith, lead brace-rods 23 and 24, the former being secured at its outer extremity to the cap 22 on mast 20, and the latter being secured at its outer end to the outer extremity of the crane-boom 3. From the revoluble sleeve 21 on the mast 20, and from the swinging circle 7, lead braces 25, attached at their outer ends to the outer extremity of extension-piece 6. From sleeve 21 also lead braces 26, secured at their lower ends to and supporting swinging circle 7 upon the supplemental boom. It will be seen that this arrangement of braces permits the crane to be swung upon its mast without interfering with the braces leading from the mast 2 to the car 50 and permits the extension-piece 6 to be swung upon its pivotal support independently of the crane without interfering with the braces by which it is stayed and strengthened.

My dipper or shovel is provided with a bail 17^a, (see Figs. 7, 8, and 9,) dipper-handle connections 17^b, and brace connections 17^c. The inner margin of the upper edge of the dipper has securely riveted thereto an iron strip 17^d bent at intervals, as shown in Fig. 9, to leave a space or recess between this iron strip and the side of the dipper or shovel. Into the forward pair of these recesses the ends of the bail 17^a are pivotally secured by pins 17^e, passing through the side of the shovel, through the end of the bail, and through the strip 17^d. The arms 17^b of the dipper-handle 11 are similarly secured in the other pair of recesses by

pins 17^f, and brace 17^c engages the extremities of the forward band or hoop 17^e from the inner side. This arrangement of the pivotal supports of the dipper or shovel upon its inner sides presents a comparatively smooth and unbroken surface to the banks or slopes of the cut and obviates the ragged and uneven surfaces necessarily resulting from the use of excavator-shovels of ordinary construction, in which the pivotal supports are on the outside of the shovel.

The operation of my device as thus far described is as follows: Assuming that the parts are assembled as stated, that the machine is in position, and that a ditch, trench, or like excavation is to be made, rack and pinion 12 13 are held by means of friction wheel and band 14 15, chain 18 is paid out, and dipper 17 swings downwardly until its teeth engage the earth, the dipper-handle meanwhile being allowed to descend by loosening the grip of friction-band 15 on its wheel 14. The dipper-handle is now held against yielding longitudinally by means of the friction band and wheel, while the hoisting-engine pulls upon the chain 18, causing the shovel to cut its way toward the car 1 until it is clear of the earth. The crane 2 3 4 is now swung to any desired point, the shovel or dipper is dumped in the usual manner, and the crane is swung back in position for the next cut of the dipper or shovel. If the cut of the shovel is to be on either side of the central line of the machine, and if the cut is to be parallel with such central line, the crane is swung in the usual manner, while engine 10 on the crane of the machine is set in motion, thereby causing rope 8 to be paid out from one side of the drum 9 and wound upon the other side of the drum, as shown in Fig. 2, thus swinging the circle 7, and with it the extension-piece or boom 6, at an angle to the crane, as shown by the dotted lines in Fig. 2. The cutting and dumping operations are now performed in the same manner as hereinbefore described, and it will be seen that no matter at what angle the crane may be set ahead, so that the cuts of the dipper or shovel shall always be parallel with each other, thus obviating the radial cuts which impart to the bank or slope a ragged and uneven appearance. As the work progresses, the machine is backed away from the cut, the operation of the dipper or shovel being constantly toward the machine. I do not, however, limit my invention to a dipper cutting toward the machine, as it is quite obvious that with slight modifications, my machine could be made to operate in the opposite direction. The method of construction and operation shown will, however, be found preferable in practice.

When it is desired to use my machine for the purposes for which an excavating-machine is commonly used, the braces 23, 25 and 26 may be removed, mast 20 unstepped, rope 8

removed from its drum and the extension-piece or boom 6 with its attachments slipped from its place, and the dipper and its handle and hoisting-chain may be reversed and placed in the crane in the usual manner, as illustrated in Fig. 8.

What I claim as my invention, and desire to secure by Letters Patent, is—

1. In an excavating machine, a crane in combination with a supplemental boom or extension-piece, means for pivotally securing said boom or extension-piece to and suspending it from the outer end of said crane, means for swinging said crane, and means for swinging said supplemental boom or extension-piece independently of each other, and a dipper or shovel operatively mounted upon said extension-piece whereby said dipper may be caused to cut in parallel lines, substantially as and for the purpose specified.
2. In an excavating machine, a crane, a supplemental boom or extension-piece pivotally secured to said crane, a mast or brace post (20,) on the outer extremity of and rigid with said crane, braces connecting said mast with the opposite end of said crane, and braces pivotally connecting said mast with said pivoted extension-piece, in combination with means for swinging said crane, and means for swing-

ing said extension-piece independently of said crane, substantially as and for the purpose specified.

3. In combination with an excavator-crane, and an extension-piece pivotally attached thereto, a mast or brace-post mounted rigidly on the outer extremity of said crane, a housing in said mast, guide-sheaves in said housing, a dipper or shovel mounted on said extension-piece, and a hoisting-chain running between said guide-sheaves and secured to said dipper or shovel, substantially as and for the purpose specified.

4. In an excavating-machine, a crane comprising the mast, boom and brace, a supplemental boom or extension-piece, mounted thereon, means for removably connecting said supplemental boom or extension-piece with said crane, a dipper handle, and a dipper thereon, in combination with means on said crane and on said extension-piece for interchangeably receiving and actuating said dipper and dipper-handle, substantially as and for the purpose specified.

JAMES KEWLEY.

In presence of—

D. C. WALTER,
W. P. TYLER.
